EJECTOR MECHANISM FOR ADDRESSING MACHINES

Application filed August 27, 1927. Serial No. 215,924.

The main objects of this invention are to provide an improved form of ejector for removing cards, stencils, plates or the like seriatim from a machine through which they are fed; to provide an improved ejector for removing cards and the like from a horizontal guideway along which they are fed edgewise in a step-by-step movement; to provide an ejector of this kind having improved means for sweeping the cards downwardly to an upright position below the plane of the guideway; to provide releasable means for momentarily supporting one edge of the card immediately prior to its ejection from the guideway; to provide an improved form of clamp for securing the card to the sweep during its movement from the guideway to its upright position; to provide improved means for releasing the clamp when the card reaches its upright position; to provide improved means for supporting a tray in position to receive the cards from the guideway; to provide improved means for guiding the cards into the tray; and to provide an ejector mechanism of this kind which is particularly adapted for use in addressing machines for removing stencils and cards from the horizontal guideway and returning them to a tray.

An illustrative embodiment of this invention is shown in the accompanying drawing wherein:

Figure 1 is a fragmentary plan of an ejector mechanism to which this invention is applied.

Fig. 2 is an enlarged detail, partly in section, showing the releasable means for holding the cards in an upright position on the transverse guideway.

Fig. 3 is a transverse vertical section of the ejector mechanism.

Fig. 4 is an enlarged horizontal section, taken on the line 4—4 of Fig. 3.

Fig. 5 is a transverse vertical section, taken on the line 5—5 of Fig. 1.

Fig. 6 is a similar section, taken on the line 6—6 of Fig. 1.

Fig. 7 is a vertical section, taken on the line 7—7 of Fig. 3.

Figs. 8 and 9 are views similar to Fig. 6.

but showing different positions of the sweep.

An improved ejector mechanism to which this invention is applied is adapted for use in connection with various types of machines but, in the embodiment herein shown, it is applied to an addressing machine. Inasmuch as the present invention relates particularly to the ejector mechanism, certain parts of the addressing machine not relating thereto and believed unnecessary to a complete understanding of the invention have been omitted from the drawings.

In the form shown, the improved ejector is applied to an addressing machine having a horizontal guideway along which the stencils and cards are fed in a step-by-step movement to a printing mechanism, which is controlled in its operation by a suitable selector mechanism arranged to coact with the stencils.

The improved ejector is located adjacent the discharge end of the guideway and includes an oscillating arm or sweep movable through a quadrant and arranged to engage the stencils seriatim for sweeping them downwardly into an upright position on a second guideway. Located adjacent the discharge end of the second guideway, is an improved support adapted to hold a tray in position to receive stencils directly from the second guideway.

In the form shown, the addressing machine comprises a frame 1 having an endless chain conveyer 2 provided with spaced lugs 3 adapted to engage apertures 4 in cards and stencils 5 for moving the cards and stencils edgewise along a horizontal guideway 6 formed by spaced guide rails 7 and 8. Suitable mechanism, not shown, is provided for moving the conveyer 2 step-by-step to feed the stencils seriatim to the printing mechanism and to the improved ejector at the discharge end of the guideway.

Adjacent the discharge end of the guideway 6, the rail 7 is recessed, as shown at 9, to permit the stencils to be swept downwardly from the guideway. The extremity of the rail 8 is spaced inwardly from the discharge end of the guideway 6 to leave an opening 10 through which the sweep of the ejector is

adapted to move. Seated in the recess 9, is a yieldable strip 11, which is normally urged by springs 12 into position to support the rear edge of a stencil immediately prior to the 5 operation of the ejector. The upper edge of the strip 11 is bevelled, as shown at 13, so as to permit the slide to be readily retracted under the pressure of the sweep, as herein-after described. Formed in the upper part 10 of the rail 7, adjacent the recess 9, are recesses 14 through which certain portions of the sweep pass.

In the embodiment illustrated, the improved ejector includes a sweep or arm 15 having bearing parts 16 and 17 journaled on a shaft 18 which is supported by a pair of fixed brackets 19 mounted on the frame 1. The shaft 18 is located adjacent the recess 10 and is substantially parallel to the guideway 20 so as to permit the arm 15 to engage the upper face of an adjacent stencil. The bearing part 16 of the arm 15 has a bifurcated part 20 provided with a pin 21 for pivotally connecting the arm 15 with a reciprocating link 22. The link 22 is reciprocated by a 25 crank 23, which is adapted to be intermittently actuated by suitable mechanism for imparting an intermittent oscillation to the sweep 15. The arm 15 is adapted to be rocked 30 downwardly through a quadrant for sweeping the stencil from its horizontal position in the guideway 6 to an upright position in a second guideway 24, which is provided with an arcuate approach 25 located below the 35 discharge end of the guideway 6.

Formed on the arm 15, are lugs 23 adapted to pass through the recesses 14 for retracting the strip 11 upon the down-stroke of the sweep.

40 Fixed on the shaft 18 between the bearings 16 and 17, is an eccentric 27, upon which is journaled the bearings 28 and 29 of a clamp 30. The arm 15 and clamp 30 are arranged to form a pair of jaws adapted to grip opposite 45 sides of a stencil during the downward movement of the arm. The clamp 30 is yieldingly urged toward the arm 15 by a spring 31 secured at one end to the bearing part 16 and at its other end to a pin 32 mounted on the bearing 28.

50 Formed on the bearing 29, is a lug 33 adapted to engage an adjustable stop pin 34 threaded in the bracket 19, for limiting the upward movement of the clamp 30. When 55 the clamp 30 is in its uppermost position, it forms an extension of the guide rail 8 so as to support the forward edge of a stencil. The arm 15 is adapted to be raised sufficiently to 60 permit the stencil to move onto the clamp 30 and strip 11.

65 Due to the eccentric arrangement of the clamp 30, when it is rocked downwardly under the action of the arm 15, it simultaneously moves radially inwardly relative to the

arm 15, so as to become disengaged from the stencil at the limit of its down-stroke.

In the form shown, the guideway 24 is located below the guideway 6 and is disposed at substantially right angles thereto. The 70 guideway 24 includes a bottom 35 forming an extension of the chute or approach 25, and a pair of side walls 36 having rails 37 adapted to slidably support a follower 38.

75 Formed in the side walls 36 adjacent the approach 25, are openings in which are pivotally mounted detents 39 having tips 40 adapted to project into the guideway 24 for securing the stencils against any backward movement upon the up-stroke of the sweep 15. 80 Bearing against the detents 39, are springs 41 adapted to permit retraction of the tips 40 to enable the stencil to pass the detents upon the down-stroke of the sweep.

85 Arranged at the discharge end of the guideway 24, is an inclined runway 42 forming a continuation of the bottom 35 for guiding the stencils and cards into a tray 43 resting on an improved bracket 44 below the runway. Mounted on the walls 36 above the runway 42, is a pair of guides 45 adapted to engage the upper edges of the stencils for securing them against forward tilting.

90 The rails 37 extend beyond the runway, so as to permit the follower 38 to move outwardly a sufficient distance to enable the stencils to travel below the follower. Outward movement of the follower 38 is limited by stops 46 formed on the extremities of the 95 rails 37.

100 Slidably mounted in the tray 43, is a follower 47 which is adapted to be moved along the tray by the advancing stack of stencils.

The tray 43 is not connected to the runway 42, but merely rests upon the bracket 44.

105 In the specific form shown, the bracket 44 comprises an arcuate bottom 48 having side flanges 49 for retaining the tray on the bracket. Located at the inner end of the bracket 44, is a bearing or shoulder 50 for supporting the inner end of the tray. The outer end of the tray rests upon the forward extremity of the bottom 48. The bottom 48 is curved so as to permit the tray to be slid rearwardly below the runway 42 and into engagement with the bearing 50. The bracket 44 is spaced from the runway 42 so as to permit the tray to be inserted between the runway and the bracket.

110 In operation, the stencils 5 are fed step-by-step along the guideway 6 while the sweep 15 is oscillated intermittently. When the sweep 15 reaches the limit of its up-stroke, it pauses momentarily to permit a stencil to move onto the supporting strip 11 and clamp 30. While the conveyer chain 2 remains stationary, the 115 link 22 is actuated to move the arm 15 downwardly through a quadrant, thereby sweeping the stencil downwardly into an upright position in the guideway 24. As the arm 15 moves downwardly, it retracts the strip 11 120

130

and causes the clamp 30 to grip the stencil. When the arm 15 reaches the limit of its down-stroke, the clamp 30 becomes disengaged from the stencil, due to the eccentric mounting of the clamp. The stencil is pushed past the detent tips 40 by the arm 15 and the latter then moves upwardly to its initial position before the next succeeding stencil is fed forwardly.

10 The stencils move along the guideway 24, down the runway 42 and into the tray 43. When the tray 43 is filled it may be readily replaced by an empty one.

15 Although but one specific embodiment of this invention has been herein shown and described, it will be understood that numerous details of the construction shown may be altered or omitted without departing from the spirit of this invention as defined by the following claims.

20 We claim:

1. The combination with a horizontal guideway along which cards are adapted to be fed edgewise seriatim, of an ejector comprising an arm pivotally mounted adjacent one side of the guideway on an axis disposed longitudinally of said guideway, said arm being adapted to extend above the guideway for engaging the upper face of a card, mechanism for moving said arm through a quadrant to sweep the card downwardly into an upright position, the initial movement of said sweep being normal to the plane of said card, said arm engaging the card during the entire 35 quadrantal movement, and means for feeding the cards along said guideway into position to be removed by said arm.

2. In a device of the class described, a guideway for cards, a yieldable portion in said guideway adapted to support a card, and an ejector movably mounted adjacent said yieldable portion and adapted to engage one face of the card for sweeping the card into a plane transverse to the plane of the guideway.

45 3. In a device of the class described, a guideway for cards, a yieldable portion in said guideway adapted to support a card, and an ejector movably mounted adjacent said yieldable portion and adapted to engage one 50 face of the card for sweeping the card into a plane transverse to the plane of the guideway, said yieldable portion being adapted to yield for releasing the card under the pressure of said ejector.

55 4. The combination with a guideway for cards, of an ejector movably mounted adjacent the guideway and adapted to engage a card for sweeping it into a position transverse to the plane of the guideway, said ejector acting normally to the plane of said card and being adapted to support the card during said sweeping action.

60 5. The combination with a guideway for cards, of a sweep movably mounted adjacent the guideway and adapted to engage one face

of a card for sweeping it into a position transverse to the plane of the guideway, and yieldable means for securing the card to said sweep during said sweeping action.

6. The combination with a horizontal guideway along which cards are adapted to be fed edgewise seriatim, of an ejector comprising an arm pivotally mounted adjacent one side of the guideway, said arm being adapted to extend above the guideway for 70 engaging the upper face of a card, mechanism for rocking said arm to sweep the card downwardly into an upright position, a clamp for securing the card to said arm during said sweeping action, and means for releasing said clamp when the card reaches an upright position.

7. The combination with a horizontal guideway along which cards are adapted to be fed edgewise seriatim, of an ejector comprising a pair of jaws pivotally mounted adjacent the guideway for engagement with a card, and mechanism for rocking said jaws to sweep the card downwardly into an upright position.

8. The combination with a horizontal guideway along which cards are adapted to be fed edgewise seriatim, of an ejector comprising a pair of jaws pivotally mounted adjacent the guideway for engagement with a card, and mechanism for rocking said jaws to sweep the card downwardly into an upright position, said jaws being eccentrically arranged whereby the rocking of said jaws moves one jaw radially relative to the other 90 so as to release the card when the card reaches an upright position.

9. In a device of the class described, a guideway for sheets, a yieldable section in said guideway, and means for pressing the sheets against said section to discharge them from the guideway.

10. In a device of the class described, a pair of spaced guide rails along which cards may be fed edgewise, a yieldable section in 110 one of said rails, and means for pressing the cards against said section to discharge them from said rails.

11. The combination with a horizontal guideway along which cards may be fed flatwise seriatim, of a sweep mounted adjacent said guideway and adapted to engage one face of a card for sweeping the card through a quadrant from horizontal to vertical position, said sweep engaging the card during 120 the entire quadrantal movement, mechanism for actuating said sweep, and means for feeding the cards flatwise along said guideway into position to be removed by said sweep.

12. The combination with a horizontal guideway along which cards may be fed flatwise seriatim, of a sweep pivotally mounted adjacent said guideway and adapted to engage one face of a card for sweeping the card 130

through a quadrant from horizontal to vertical position, the pivotal axis of said sweep being disposed longitudinally of said guideway, said sweep engaging the card during the entire quadrantal movement, mechanism for actuating said sweep, and means for feeding the cards flatwise along said guideway into position to be removed by said sweep.

13. The combination with a horizontal guideway, means for intermittently moving cards flatwise along said guideway, of a sweep pivotally mounted adjacent said guideway and adapted to engage one face of a card for sweeping the card through a quadrant from horizontal to vertical position, said sweep engaging the card during the entire quadrantal movement, and mechanism for actuating said sweep during an intermission in the card feeding operation.
14. The combination with a horizontal guideway for supporting cards, of a sweep pivotally mounted adjacent said guideway and adapted to engage the top face of a card for positively sweeping the card downwardly through a quadrant from horizontal to vertical position, said sweep engaging the card during the entire quadrantal movement, and means for feeding the cards flatwise along said guideway into position to be removed by said sweep.

Signed at Chicago this 20th day of August, 1927.
